(57) **CLAIM**

The ornamental design for a raised air bed, as shown and described.

DESCRIPTION

FIG. 1 is a perspective view of the raised air bed of the present invention.

FIG. 2 is a top plan view of the raised air bed of the present invention.

FIG. 3 is a left side elevation view of the raised air bed of the present invention.

FIG. 4 is a right side elevation view of the raised air bed of the present invention.

FIG. 5 is a bottom plan view of the raised air bed of the present invention.

FIG. 6 is a front elevation view of the raised air bed of the present invention; and,

FIG. 7 is a rear elevation view of the raised air bed of the present invention.

The broken line showing an environmental structure is for illustrative purposes only and forms no part of the claimed design.
